PUMP

Leslie L. Aspelin, Cleveland Heights, Ohio, assignor to
Thompson Ramo Wooldridge Inc., a corporation of
Ohio

Application March 17, 1954, Serial No. 416,792

2 Claims. (Cl. 103—126)

This invention relates to a pump especially useful for power steering apparatus or the like to supply a relatively constant rate of flow of liquid at a predetermined pressure regardless of wide variations in operating speeds. Specifically, this invention relates to a unit adapted to be easily attached to the rear face of an automobile engine generator and having a pinion and ring gear pump therein driven from the generator and submerged in the fluid which it pumps to flow control and relief valves that deliver a rated flow of fluid from the unit at less than a predetermined maximum pressure throughout a wide range of pump speeds while storing and cooling excess fluid in the unit.

While the pump of this invention will be hereinafter specifically described as embodied in a power steering apparatus for an automobile, it should be understood that the pump of this invention is generally useful in pumping hydraulic fluid at a substantially constant rate and at less than a predetermined maximum pressure regardless of the speed of operation of the pump. The feature of submerging the pump in a bath of the liquid which it pumps, is applicable and especially useful in power steering apparatus to provide a reservoir for the hydraulic liquid, such as oil, to lubricate the pump and to cool the liquid.

In accordance with this invention a rotary pump of the rotating ring gear and pinion type is mounted inside of a finned housing from which it receives liquid to be pumped. The pump casing has an end head with a peripheral groove. The end head is adapted to be abutted against the end face of the generator and a clamping ring locked in the groove attaches the unit to the generator. A hollow hub carried by the end head is adapted to receive, in splined relation, a drive shaft from the generator. The pinion of the pump is keyed on this hub. Fluid is fed from the bottom portion of the housing through a side face of the gear and pinion into the tooth chambers and is discharged from the tooth chambers out of the opposite side face of the assembly into a passageway containing a spring biased orificed valve. This valve controls the rate of discharge from the pump and whenever the pressure differential on opposite sides of the orifice thereof exceeds a predetermined value, the valve will be shifted to uncover a port communicating with the interior of the housing for dumping the pump fluid back into the housing from which it was received. The outlet passage from the pump also is vented to a pressure relief valve communicating with the interior of the housing so as to protect the pump and the system in which the pump operates against excess pressure. Fluid at the working pressure and at the working rate is thereby discharged downstream from the orificed valve and from the relief valve to be conveyed by a tube to a power steering actuator or the like. The fluid is returned through a second tube back to the housing from which it is again recirculated to the pump. The fins on the housing will radiate heat from the fluid. The fluid will also lubricate the pump, and the housing,

2

in addition, serves as a reservoir for the working fluid of the system.

It is then an object of this invention to provide a pump unit having its own reservoir for working fluid and adapted to be operated throughout a wide range of speeds for delivering a substantial constant flow rate by recirculating excess fluid to the reservoir whenever the flow rate exceeds a predetermined value and whenever the working fluid exceeds a predetermined pressure.

10 Another object of the invention is to provide a submerged pump assembly adapted to be clamped on the back face of an automobile generator to be driven thereby and having a metering valve and a relief valve for controlling the flow rate and the maximum pressure developed by the pump.

Another object of this invention is to provide a power steering pump having its own hydraulic fluid reservoir adapted to be mounted on a generator of an automobile engine to be driven by the generator and adapted to cool the hydraulic fluid.

A still further object of this invention is to provide a pump of the rotating ring gear and pinion type receiving fluid to be pumped through one side face and discharging the pump fluid through an opposite side face to a flow control valve adapted to dump excess fluid into a reservoir surrounding the pump while maintaining a constant delivery rate for the pump.

A still further object of this invention is to provide a submerged rotating ring gear and pinion type pump 30 having an inlet on one side face thereof receiving liquid from the bottom of a reservoir and having an outlet on the opposite side face delivering the fluid to a discharge passageway containing an orificed metering valve which will dump excess liquid back to the reservoir to be cooled therein before being recirculated to the pump.

Other and further objects of this invention will be apparent to those skilled in the art from the following detailed description of the annexed sheets of drawings which, by way of a preferred example only, illustrate one embodiment of the invention.

On the drawings:

Figure 1 is a somewhat diagrammatic elevational view of a pump of this invention mounted on the generator of an automobile engine for supplying working liquid to a power steering apparatus for the vehicle which is driven by the engine.

Figure 2 is an enlarged front end elevational view of the pump along the line II—II of Figure 1.

Figure 3 is a longitudinal cross-sectional view of the pump taken along the line III—III of Figure 2.

Figure 4 is a cross-sectional view, with parts in elevation, taken along the line IV—IV of Figure 3.

Figure 5 is a cross-sectional view, with parts in elevation, taken along the line V—V of Figure 3.

Figure 6 is a cross-sectional view taken along the line VI—VI of Figure 3.

As shown on the drawings:

In Figure 1, the pump 10 is shown as mounted on a generator 11 of an automobile engine 12. The engine 12 has a crankshaft driven pulley 13 driving a fan belt 14. The belt 14 drives the fan pulley 15 for rotating the fan 16 of the engine. A pulley 17 on the generator 11 engages the fan belt 14 to be driven thereby. The generator shaft 18 is joined by a coupling 19 to the pump shaft 20.

As best shown in Figure 3, the pump casing 21 has a large end head 22 at one end thereof bolted to the main body 23 of the pump by means of bolts such as 24 shown in Figure 4. The end head 22 has an external V-groove 25 around the periphery thereof adjacent its flat outer face 26 and this flat outer face 26 is adapted to abut the flat outer face 27 of the generator housing which also has a V-shaped groove 28 therearound. A clamping ring 29

extends into both grooves 25 and 28 to lock the end head on the generator and thereby mounts the pump. This clamping ring 29 can be tightened by the means of the usual drawbolt clamp 30 or the like.

The pump casing 21 is enclosed by an outer housing 31 of substantially cup-shape with an open end 32 receiving the end head 22 of the pump. A groove 33 in this end receives a sealing ring 34 for sealingly engaging the inner face of the housing adjacent the open end 32.

Longitudinal cooling fins 35 radiate from the housing 31 around the periphery thereof. A filling port 36 is provided in the top of the housing and is closed by a snap-in cover 37.

The closed end wall 31a of the housing 31 has bosses 38 and 39 therein carrying fittings 40 and 41. The fitting 40 is threaded into a discharge passage 42 formed in the casing body 23. The fitting 41 communicates with the interior of the housing 31 near the bottom thereof.

The end head 22 has a central hub portion 43 with an enlarged outer bore 44 terminating at a shoulder 45 and carrying a seal 46 against the shoulder. A smaller bore 47 continues inwardly from the shoulder and carries roller bearings 48 for rotatably supporting a hollow shaft 49 with spline teeth 50 in the interior thereof intermediate the ends. The shaft extends beyond the end head 22 into a recess 51 in the body 23 and roller bearings 52 are seated in this recess to carry the shaft extension. A knurled plug 53 is pressed fit into the end of the shaft 49 adjacent the bottom of the recess 51 to seal the interior of the shaft from the recess.

A pump pinion 54 is keyed on the shaft 49 intermediate the ends thereof by means of a key 55 and a pump ring gear 56 surrounds the pinion 54.

The inside face 57 of the end head 22 receives one side face of the pinion 54 and ring 56 thereagainst and an arcuate inlet port 58 in this end face is connected through a passageway 59 in the end head with the interior of the housing 31 at the bottom thereof. The mouth of this passageway is covered by a screen 60. A blind arcuate recess 61 is also provided in the end face 57 in opposed relation to the port 58. The main body 23 has an outlet opening 62 opposing the port 61 on the opposite face of the ring and pinion and communicating with the discharge passageway 42.

The pinion 54 and ring 55 fit in a recess 23a in the end face of the body 23 adjacent the end head 22.

As best shown in Figure 6, the pinion has external teeth 54a around its periphery and the ring gear has mating teeth 56a around its inner periphery with the pinion containing one less tooth than the ring gear. The tooth shape is such that during rotation of the two gears, a plurality of expanding and contracting pumping chambers 63 is formed in the inter-tooth spaces.

When the shaft 49 rotates the pinion, the ring gear is driven from the teeth 54a of the pinion and liquid enters into the open pumping chambers 63 along the extent of the inlet port 58. The axis of the shaft 49 on which the pinion is mounted is eccentric to the bore recess 23a of the housing 23 in which the ring gear rotates and liquid is trapped in the pumping chambers 63 to be propelled to the outlet ports 61 and 62. The provision of the port 61 opposite the outlet port 62 balances the load on opposite faces of the ring gear and pinion and provides a smooth discharge of liquid. The liquid is ejected as the pumping chambers 63 are reduced in volume due to the mated engagement of the teeth and it will be noted that as the teeth leave the outlet ports, they are in fully mated relationship so as to seal the outlet from the inlet ports. As the teeth enter the inlet port they become mated to open up the pumping spaces therebetween and as they continue between the inlet and outlet ports, the apices of the teeth sealingly engage each other to maintain the trapped fluid therein.

The outlet passageway 42 of the pump slidably receives a spring 64 loaded flow control valve 65 in the

form of a thimble with an orificed end wall 65a having an orifice 66 therethrough sized for maintaining a predetermined pressure drop between the upstream and downstream sides thereof. The valve 65 slides in the bore of the passageway to cover and uncover a port 67 communicating with the interior of the housing 31 and, as the valve uncovers this port, fluid will be returned from the passageway 42 back to the interior of the housing. The port 67 is vented at 68 to the recess 51 so that any pressure exerted on the end of the pump shaft due to leakage from the pump will be vented to inlet and will not provide a thrust load on the assembly.

A port 69 in the passage 42 downstream from the valve 65 is connected through a passage 70 in the body 23 with a bore 71 in the front wall of the body 23. A valve seat 72 is formed at the bottom of the bore 71 and a ball member 73 in a carrier 74 which is slideable in the bore 71, is spring-urged by a spring 75 against the seat to control flow from the passage 70 to an outlet 76 communicating with the interior of the housing. A plug 77 is threaded into the bottom of the bore 71 to bottom the spring 75. The plug can be adjusted to vary the spring load for varying the load at which the valve 73 will open.

Operation

In operation, hydraulic liquid to operate the power steering apparatus 78 of Figure 1 is introduced into the housing 31 to substantially fill the housing and thereby surround the pump body 23. This liquid will cover the inlet 59 and when the engine 12 is operated to drive the generator 11, the pump shaft 20 will rotate the pump shaft hub 49 to thereby drive the pinion 54. The pinion, in turn, drives the ring gear 56 and the liquid is propelled to the passageway 62 where it acts on the end face 65a of the valve 65 and partially depresses this valve against the action of the loading spring 64. Fluid flows through the orifice 66 and is delivered through the fitting 40 to a feed tube 79 into the actuator 80 of the power steering apparatus 78. A valve (not shown) in the power steering apparatus, is controlled by the steering wheel 81 on the steering column 82 and this valve regulates the admission and release of the fluid to the actuator. The pitman arm 84 is thereby power driven from the power steering apparatus 78.

A return tube 85 returns the liquid to the fitting 41 which deposits it back to the housing 31. In the event that the actuator 80 is inactive and does not require fluid for operation, the pressure differential across the valve 65 will increase to further depress the valve against the load of the spring 64, thereby opening up the port 67 to return the liquid back to the interior of the housing. The degree of opening of the port will determine the relative proportion of liquid fed to the feed tube and the proportion returned to the interior of the housing. In the event that back pressure exceeds a predetermined maximum, the check valve 73 will be opened to relieve the pressure downstream from the flow control valve.

The feature of providing the inlet port 58 and the outlet 62 of the pump on opposite sides of the pinion and ring gear, affords a very compact balanced arrangement.

The feature of submerging the pump in the hydraulic liquid and the placing of cooling fins on the housing for the pump, maintains the hydraulic liquid in a cooled condition.

The pump of this invention is, therefore, adapted to deliver fluid at an essentially constant rate to the actuator of the power steering apparatus without developing excess pressures regardless of the varied speed of operation. When the pump is operated at slow speeds due to the idling of the engine 12, the flow metering valve 65 will be closed. As the engine speed increases, the valve will be partially opened to relieve excess flow back to the pump interior.

It will be understood that variations and modifications

may be effected without departing from the scope of the novel concepts of this invention.

I claim as my invention:

1. A pump adapted to be detachably mounted on an automobile engine driven generator to be driven from the engine through the generator shaft for supplying fluid under pressure to fluid motor means which comprises a cylindrical end head having a peripheral mounting groove therearound adjacent a first face thereof and a peripheral seal ring groove therearound adjacent the opposite second face thereof, a pump body of smaller diameter than said end head having a first end face abutting the second face of the end head, said pump body and said end head having aligned bores, said pump body having a recess in the first end face thereof surrounding said bore in the body, bearings in each bore on opposite sides of said recess, a pump shaft mounted on said bearings, a pump rotor in said recess driven by said shaft, said end head having an inlet in said second face joined with said recess, said body having an outlet passage joining the recess with a second end face of the body, a cup-shaped housing having the open mouth thereof seated over the end head around the seal ring groove thereof and terminating short of the mounting groove, a seal ring in the ring groove sealingly engaging the mouth of the housing, said housing having the closed end wall thereof abutting the second end face of the body, said housing end wall having a first opening aligned with the outlet passage of the body and a second opening spaced from the body, an outlet tube fitting extending through the first opening and threaded into said outlet passage, a flange on said outlet tube fitting abutting the outer face of the housing end wall to clamp the housing to the second end face of the body and hold the housing on the end head, an inlet tube fitting threaded in said second opening, and said housing having a filler opening to admit fluid for submerging the pump body and for covering the pump inlet in the end head.

2. A pump adapted to be detachably mounted from an end head thereof which comprises an end head having mounting means thereon adjacent a first face thereof and a peripheral seal ring groove therearound adjacent the opposite second face thereof, a pump body of smaller diameter than said end head having a first end face abutting the second face of the end head, said pump body and end head having aligned bores, a pump recess surrounding a bore,

45 740,738

bearings in each bore on opposite sides of said recess, a pump shaft supported on said bearings, a pump rotor in said recess driven by said shaft, said end head having an inlet passageway with an inlet port in said second face externally of the pump body, and said passageway being joined with said recess, said body having an outlet passage joining the recess with a second end face of the body, a cup-shaped housing having the open mouth thereof seated over the end head around the seal ring groove thereof and terminating short of the mounting means, a seal ring in the groove sealingly engaging the mouth of the housing, said housing having the closed end wall thereof abutting the second end face of the body, said housing end wall having a first opening aligned with the outlet passage of the body and a second opening spaced from the body, a flanged outlet tube fitting extending through the first opening and threaded into said outlet passageway with the flange thereof thrusting against the outer face of the housing end wall to clamp the housing to the second end face of the body and to hold the housing on the end head, an inlet tube fitting threaded in said second opening, and said housing having a filler opening to admit fluid for submerging the pump body and for covering the pump inlet in the end head.
